UNITED STATES PATENT OFFICE

REINHOLD RIESCHICK, OF NEW YORK, N. Y.

PIANO-ACCORDION

Application filed March 28, 1932. Serial No. 601,587.

This invention relates to improvements in piano-accordions, banjos and similar musical instruments, and is particularly directed to the casings or housings supporting the key controlled devices and whereby said devices or operative parts are rigidly supported against working strains, thus maintaining perfect alignment and constant co-active relative positions of the moving treble elements of the musical instrument, and wherein changing climatic conditions have no disarranging effect.

A principal object of the invention is to produce improved housings for the treble and bass mechanisms to eliminate distortions in said mechanisms for the purpose of prolonging the satisfactory service life of the structural parts of a musical instrument of the piano-accordion type.

Inventive features of the invention are seen in the provision of all-metal housings and a laminated metallic valve panel built into the walls of the treble housing of the accordion, consisting of upper and lower fixed metal plates and a tone controlling slidably mounted valve plate operable therebetween.

A further feature of the invention includes the provision of an all-metal housing containing the treble parts of the piano-accordion; said housing including a piano-keyboard portion and a base portion, constituting the sound chamber, and being of one piece or unitary construction and of suitable resonant metal, for increasing the tonal qualities and rigidity of the structure.

The invention furthermore has for an object, the production of a piano-accordion of this character having the functions and advantages noted and at the same time enhancing the appearance of the musical instrument by reason of an entire metal surface which is susceptible of many desirable ornamental finishes, and it will be understood that the invention is not limited to any particular physical embodiment but may be expressed in different structures and forms within the scope of the invention claimed.

A preferred and principal feature of con-

struction is in forming a keyboard back portion at the top with a channel or guideway, and also with end flanges, and further, in extending the said keyboard back portion horizontally over the sound chamber to constitute the lower plate of the said laminated ported valve panel for adding strength to the built up treble housing.

In the drawings, similar reference characters are employed to designate corresponding parts throughout the several views thereof, in which:

Fig. 1 is a partial diagrammatic sectional elevation, showing the treble and bass housings or casings for supporting the active parts (not shown) of a piano-accordion, and an interposed bellows; and further, indicating by dotted lines the usual reed-blocks located within the said treble housing, but omitting the reed blocks of the bass side of the instrument as well as other elements of the device.

Fig. 2 is a detail plan view of the slidable portion or damper of the sectional ported interposed plate of a laminated ported panel built into the base portion of the said treble housing.

Fig. 3 is a detail section, taken on the line 3—3 of Fig. 1, showing certain parts whereby the damper plate is actuated.

Fig. 4 is a vertical cross-sectional view taken on the line 4—4 of Fig. 1, with the ports of the panel in the full-tone position, and looking as the arrow points, but showing the right end portion of the treble casing only.

Fig. 5 is a partial horizontal section, taken on the line 5—5 of Fig. 4, showing the ported panel in plan view, with parts broken away to disclose clearances for movements of the damper plate, and the relation of the ports.

Fig. 6 is a detail section on the line 6—6 of Fig. 5, showing how certain sectional parts of the damper plate are fixedly attached to the upper and lower plates of the ported panel to form a laminated structure.

Fig. 7 is a detail section taken on the line 7—7 of Fig. 5, showing how another section of the interposed plate is secured in place between the upper and lower lamina of the ported panel.

Fig. 8 is a detail sectional view taken on the line 8—8 of Fig. 4, showing a pivotal mounting for a part of the damper plate actuating means.

Referring to the drawings in detail, 10 designates generally a piano-accordion of the better type, with the key parts and reed blocks removed or omitted, in which the all-metal housing 11 of the treble side of the structure is joined to the all-metal housing 12 of the bass side thereof, by the usual bellows 13; the usual shoulder and wrist straps for supporting the musical instrument and for "pumping" the bellows, being omitted, as said straps form no part of the present invention.

The said all-metal housing 11 of the treble side may embody a base portion 9, forming a sound chamber 14 surrounded by suitably reinforced base forming walls 15, supporting a unitary keyboard or portion 16, having at its top and ends, integral flanges 17 collectively defining a piano key chamber 18.

A laminated ported panel 19, is built into the base walls 15, of the treble housing; said panel comprising an upper plate 20, a lower plate 21; and a central plate 22, composed of several fixed sections 23 and 23a, and a slidable damper-plate section 24, having integral ears 25, from which rounded pins 26 project for attachment to a shifting means hereinafter described. The damper-plate 24 has formed therein a series of oblong ports 27, and a series of rectangular openings 28, somewhat longer than the fixed damper-plate sections 23, to permit of limited sliding movements of said damper-plate 24, as best shown in Fig. 5.

The upper and lower plates 20 and 21, and the sections 23 and 23a of the central plate 22, are riveted together as at 29, and said plates and sections are provided with registering ports 30; the ports 27 of the damper-plate 24, being normally in registration with corresponding ports 30 of the panel 19, but are out of registration with said ports when the damper plate is shifted to dampen the tones of the piano-accordion, as will be obvious to those skilled in the art.

The usual reed-blocks, common to this type of instrument, are only indicated at 32 by dotted lines in the sound chamber 14, of Fig. 1, and similar reed-blocks are, of course, also employed in connection with the bass housing of the piano-accordion, the inner wall 32 thereof having appropriate ports 33, for tone outlet through the grill or open-work outer wall 34, of said bass housing 12; dust and dirt being excluded by a lining of suitable fabric 35.

The space between the base walls 15, above the laminated panel 19, may be termed a valve chamber 36, see Fig. 1, in which the velvets or valves of the instrument may be received to normally rest on and over their respective ports of the ported panel, and

piano-keys rockable on the center 37, (Fig. 1) operate the valves or velvets as is well known; the keys and supported velvets and the bass buttons and connections being omitted, as they form no part of this invention.

A cover for the valve or velvet chamber 36, is shown as a grill or open-work plate 38, which has a fabric lining 39, to exclude dust from said valve chamber, but permitting full exodus of musical tones therefrom.

The means for shifting the damper-plate 24 longitudinally between the fixed plates and the sections of the laminated panel plate 19, to regulate the tones of the piano-accordion, may comprise an outer manually actuated slide or shift bar 40, formed with gripping ribs 41, mounted to operate on the top flange 17 of the piano-key chamber, and which is connected by screws 42 or the like, passing through slots 43, (Fig. 3) in the said flange 17, to and through an inner slide bar 44, which in turn is provided with thickened portions 45, operating in other slots 46 in said flange 17, for limiting the movements of the shift bar; the thickened portions are provided with slots 47, to freely receive the upper ends 48, of rock-levers 49, which as in Figs. 1, 4 and 8, extend through bridge plates 50, secured to the back wall or plate 16, of the piano-key chamber 18.

The rock-levers 49 are each pivoted as at 51 to the respective bridge plates 50, and are extended downwardly and slotted as at 52 to receive their respective projecting pins 26, on the ears 25 of the damper-plate 24.

Thus it will be apparent that longitudinal movement of the top or shift bar 40, will rock the levers 49 on the pivots 51, and through the described slot and pin connections with the ears 25 and of the damper-plate 24, the same may be longitudinally actuated to control the tonal qualities of the piano-accordion, as will be readily understood.

The laminated ported panel 19, is built into the walls 15, of the said base portion of the treble housing by providing an overhanging shoulder 15a in said walls, between which and a continuous flange 52, the said panel is rigidly held, the said overhanging shoulder 15a is continued along the inner faces of the front and end walls of said base portion.

The all-metal treble and bass housings of the piano-accordion may be reinforced wherever desired to produce a sturdy, rigid, resonate structure for supporting the contained operable parts against warpage or distortion, to maintain relative uniform actions and results in a musical instrument mechanism.

An important feature of reinforcing the base portion 9, of the instrument is the provision of spaced cleats or ribs 60, disposed between the continuous flange or angle piece 52 and a continuous reinforcing strip or bar 61, secured at the bottom or edges of the base walls 15, see Figs. 1 and 4.

Another important feature, for strength and durability, is the forming of the back plate portion 16 integrally with the lower plate or lamina 21 of the ported panel, as 5 clearly shown in Fig. 1 of the drawings.

I claim :

1. In a piano-accordion structure, an all-metal casing for supporting and housing the elements operatively active for playing the 10 treble notes of the accordion; an all-metal casing for supporting and housing the elements operatively active for playing the bass notes of the accordion and a bellows co-ordinating with the said treble and bass elements, and connecting said housings for the purpose of generating air pressures and vacuums for operating the said elements to produce musical tones; said all-metal housings providing security against distortion of 20 the working elements supported thereby; and a laminated ported metal panel built into the walls of the housing supporting the treble elements of the accordion.

2. In a piano-accordion structure, an all-metal casing for supporting and housing the elements operatively active for playing the treble notes of the accordion; an all-metal casing for supporting and housing the elements operatively active for playing the bass notes 30 of the accordion and a bellows co-ordinating with the said treble and bass elements, and connecting said housings for the purpose of generating air pressures and vacuums for operating the said elements to produce musical tones; said all-metal housings providing security against distortion of the working elements supported thereby; and a laminated ported metal panel built into the walls of the housing supporting the treble elements of the 40 accordion, consisting of upper and lower fixed ported metal plates and an interposed movable ported metal plate.

3. In a piano-accordion structure, an all-metal casing for supporting and housing the elements operatively active for playing the treble notes of the accordion; an all-metal casing for supporting and housing the elements operatively active for playing the bass notes of the accordion and a bellows co-ordinating with the said treble and bass elements, and connecting said housings for the purpose of generating air pressures and vacuums for operating the said elements to produce musical tones; said all-metal housings 50 providing security against distortion of the working elements supported thereby; and a laminated ported metal panel built into the walls of the housing supporting the treble elements of the accordion, consisting of upper and lower fixed ported metal plates and an interposed movable ported metal plate; the plates of the built-in panel having normally registering ports and the movements of the interposed ported plate controlling the 60 tonal qualities of the accordion.

4. In a piano-accordion structure, an all-metal casing for supporting and housing the elements operatively active for playing the treble notes of the accordion; an all-metal casing for supporting and housing the elements operatively active for playing the bass notes of the accordion and a bellows co-ordinating with the said treble and bass elements, and connecting said housings for the purpose of generating air pressures and vacuums for operating the said elements to produce musical tones; said all-metal housings providing security against distortion of the working elements supported thereby; and a laminated ported metal panel built into the walls of the housing supporting the treble elements of the accordion, consisting of upper and lower fixed ported metal plates and an interposed movable ported metal plate; the plates of the built-in panel having normally registering ports and the movements of the interposed ported plate controlling the tonal qualities of the accordion, said interposed ported plate being manually controlled from the exterior of said accordion.

5. In combination; in a piano-accordion, a casing part constructed entirely of reinforced resonate metal for supporting the treble parts; a casing part constructed entirely of reinforced resonate metal for supporting the bass parts; a bellows connecting said casing parts; a laminated ported panel built into the walls of the treble casing part and means for slidably operating a lamina of said ported panel for the purpose set forth.

6. In combination; in a piano-accordion, a casing part constructed entirely of reinforced resonate metal for supporting the treble parts; a casing part constructed entirely of reinforced resonate metal for supporting the bass parts; a bellows connecting said casing parts; a laminated ported panel built into the walls of the treble casing part and means for slidably operating a lamina of said ported panel for the purpose set forth, said means comprising pivotally connected rock bars operable exteriorly of said treble parts supporting casing.

7. A piano-accordion embodying all-metal treble and bass frame structures and an attached bellows; the treble frame structure having a three plate ported panel of metal, including upper and lower fixed ported plates and a central sectional ported plate; sections thereof being riveted or otherwise secured to the upper and lower plates of said panel; another section of said central plate being slidable between said upper and lower plates for regulating the tone volumes; and means pivotally connected to the slidable plate for controlling its movements from without the treble frame structure.

8. A piano-accordion embodying all-metal treble and bass frame structures and an attached bellows; the treble frame structure

- having a three plate ported panel of metal, including upper and lower fixed ported plates and a central sectional ported plate; sections thereof being riveted or otherwise secured to the upper and lower plates of said panel; another section of said central plate being slidable between said upper and lower plates for regulating the tone volumes; and means pivotally connected to the slidable plate for controlling its movements from without the treble frame structure; the ports of said slidable plate being normally in registration with the ports of the said upper and lower plates of the ported panel to permit full tones to escape therethrough, while movement of the slidable plate to its extreme opposite position acts to reduce the tone volume emanating from the ports of said panel for damping effects.
20. A piano-accordion having an all-metal frame for supporting the treble keys thereof; said frame embodying a reinforced body portion; an all-metal key-board integral with said body portion; a panel built into the walls of said body portion; said panel comprising upper and lower fixed plates having registering ports, and an interposed sectional plate having ports normally registering with the ports of the other plates; sections of the interposed plate being fixedly secured; and one other section being slidable and being formed with integral ears each formed with a projecting pin; in combination with manually operable means connected with said pins, for sliding the free section of the interposed plate for damping the tones of the said piano-accordion.
10. In combination; an all-metal casing for supporting treble parts of a piano-accordion, said casing embodying a base portion and a key-board portion formed integrally one with the other; a laminated all-metal ported panel built into the walls of said base portion, a lamina of said panel being relatively slidable; an all metal casing for supporting the bass parts of said piano-accordion; a bellows connecting the said casings; and means for actuating the slidable lamina of said ported panel for damping the tones of said piano-accordion.
11. In a piano-accordion; all metal treble and bass housings and a bellows connected therewith; said treble housing embodying a base portion and a keyboard portion; a laminated ported panel built into said base portion; said keyboard portion having bent integral portions relatively forming a guide flange at its top, end flanges, and a plate, forming the lower lamina of said laminated ported panel.

Signed at Brooklyn, in the county of Kings and State of New York, this 22nd day of March, A. D. 1932.

REINHOLD RIESCHICK.
